UNITED STATES PATENT OFFICE.

MAX KRISCHER AND CHARLES ROSENBLUM, OF BROOKLYN, NEW YORK.

FASTENER FOR METAL CLIPS.

Application filed May 15, 1922. Serial No. 561,119.

To all whom it may concern:

Be it known that we, MAX KRISCHER and CHARLES ROSENBLUM, both citizens of the United States, residing at New York city, 5 borough of Brooklyn, in the county of Kings and State of New York, have invented certain new and useful Improvements in Fasteners for Metal Clips, of which the following is a specification.

10 This invention relates to clips of fastening devices such as are commonly made of bendable sheet metal or other material and attached to flexible supporting bodies, such as leather, fabric, or other articles of manufacture, either lined or unlined, the fastening in the old practice usually being performed by use of staples, rivets, screws, or the like, such usual fastening means being expensive both as to material and time of 15 operation, as well as being more or less unsightly and liable to cause the catching of the garments of the persons handling or carrying the articles.

20 Among the objects of the invention is to provide a means for fastening a metal clip or the like to a support, the fastening means being so designed as to present an unusually pleasing and attractive appearance; one that may be performed with the least possible 25 amount and weight of material of which the clip is made; one that may be made and applied with the least possible amount of expense as to time of operation and moreover one that possesses maximum strength or 30 holding power.

35 With the foregoing and other objects in view the invention consists in the arrangement and combination of parts hereinafter described and claimed, and while the invention is not restricted to the exact details of 40 construction disclosed or suggested herein, still for the purpose of illustrating a practical embodiment thereof reference is had to the accompanying drawings, in which like 45 reference characters designate the same parts in the several views, and in which—

50 Fig. 1 is a plan view of one embodiment of the invention exemplifying a sheet metal clip.

Fig. 2 is a longitudinal section of the same on the line 2—2.

Fig. 3 is a cross sectional detail on the line 3—3 of Fig. 1.

Fig. 4 is a detail view of the clip before 55 attachment.

In that form of the invention shown the supporting body 10 may be understood as being composed of leather or fabric of either single ply or laminated construction, such for example as an edge portion of a suit 60 case, brief bag, musical instrument case, or the like.

The clip 11 is of any suitable size or configuration, but shown herein as of U-shape in cross section where it embraces the edge 65 portion of the support. In flat form the clip is practically rectangular and while of such form is subjected to the action of a tool which forms therefrom a plurality of pairs of prongs 12, preferably of triangular form 70

and long enough to more than project through the support 10 when attached thereto. The prongs of each pair are so disposed with relation to each other that the bases of 75

the triangles, the sides along which the prongs are attached as an integral part of the main body of the sheet of metal, are opposite each other and with the apexes or points of the prongs extended toward each other. Thus each pair of prongs will grip 80

or embrace around a portion 10' of the support and so positively hold the same from relative movement in any direction. It will be observed also in this connection 85

that since the strain on the clip tending to separate it from the support is ordinarily in the direction of the edge of the support, the prongs are so disposed as to have the greatest possible strength resisting such tendency because such strain is received by the 90

prongs in the direction where the inherent strength is the greatest. It will be noted also that with the prongs thus stamped directly out of the body of the clip 11 no waste of material results, and with the arrangement thereof in pairs with their bases opposite each other a very attractive design 95

is produced. Without being unnecessarily restricted as to the number of pairs of prongs or as to their relative arrangement, 100 we have found in practice that usually the best form is that indicated, in which two pairs are formed from one side of the clip adjacent to the respective corners thereof, while another pair is formed from the opposite side of the clip and relatively between 105

the first two pairs. In this connection it is to be observed that, depending upon the strength and firmness of the support as a holding body, a double gripping or fasten- 110

- ing effect is accomplished by the fact that the pairs of prongs enter and pass through the support from opposite sides thereof. That is to say, the prongs from one side, 5 gripping the body or support, prevent such side of the clip from being separated from the support, while the prongs from the other side of the clip, likewise gripping the support, prevent the separation of said other 10 side from the support, and thus the fastening is complete and effective even though the material from which the clip is made may be of unusually thin and relatively pliable stock.
- 15 With the clip designed in size and length of prongs consistent with the thickness of the support it will be noted that when the prongs carried by either side of the clip are plunged or forced through the support 20 the points thereof will impinge against the inner surface of the opposite side of the clip, causing thereby directly the bending or clinching of the prongs against said opposite side and compelling the prongs of each pair 25 to grasp around or embrace a portion 10' of the body.

We claim:

A clip of sheet metal and of U-shape in cross section and having two flat side portions bendable toward each other on the 30 opposite sides of a support, one side portion having stamped therefrom a pair of triangular prongs having sharp points projected through the support and toward and clinchable against the other side portion 35 when the clip is bent as aforesaid and having their bases parallel insuring that the points when so clinched will be directed toward each other embracing a portion of the support, and the other side portion having 40 stamped therefrom, on opposite sides of the prongs aforesaid, two pairs of prongs, similar in construction and function to the pair first mentioned, whereby the grip on the engaged support of any pair of prongs is reinforced by the grip thereon of the next adjacent pair of prongs.

In testimony whereof we affix our signatures.

MAX KRISCHER.
CHARLES ROSENBLUM.
